AUTOMATIC TELEPHONE SYSTEM

Norman H. Saunders, Chicago, Ill., assignor to
 Associated Electric Laboratories, Inc., Chicago,
 Ill., a corporation of Delaware

Application February 3, 1933, Serial No. 654,977

30 Claims. (Cl. 179—18)

This invention relates in general to automatic telephone systems, but more in particular to small systems suited for installation in towns or villages. An automatic telephone system of this type is generally known as a community automatic exchange or C. A. X. Such a telephone system may be of about fifty lines capacity, more or less, and the lines would ordinarily be of various types, such as common battery lines and local battery lines, full metallic lines, and grounded lines. There usually also would be a considerable proportion of party lines, and some of these party lines may have so many subscribers on them that selective ringing is impracticable, making it necessary to resort to code ringing. A community automatic exchange generally also has to be trunk connected with one or more exchanges in adjacent cities, which may be either of the manual or automatic type. Provision must therefore be made for trunking calls to manual exchanges or for dialling into other automatic exchanges.

The object of the present invention is to produce a novel and improved community automatic exchange of the foregoing character. A special object is to provide for taking care of all of the various types of service that ordinarily are met with in the situation which is outlined above, so that a single type of exchange can be manufactured and sold for use in any community regardless of the particular requirements of that community. The exchange which I have designed may therefore be fittingly termed a universal C. A. X. A further object of the invention is to provide an exchange of this character which is unattended, that is, one which does not require the constant attention of a switchman. An unattended exchange may be left alone frequently for quite long intervals, and therefore special attention has to be paid to the possibility of certain troubles arising which might put part or all of the apparatus out of commission unless they were specially provided against.

There are numerous other objects and special features of the invention, all of which will be more fully pointed out in the detailed specification which is to follow, reference being had to the accompanying drawings.

Referring to the drawings, Figs. 1, 2, 3, and 4, when laid out in rectangular formation, with the corresponding lines at the edges of the several sheets in alignment, show sufficient of the apparatus and circuits thereof to enable the invention to be explained and understood. Fig. 5, on the

same sheet with Fig. 3, is a trunk circuit which may extend to a manual exchange.

Considering somewhat more in detail the various items of equipment which are shown in the drawings, Fig. 1 shows two subscribers' lines and the associated line circuits at the exchange. The line associated with line circuit #1 is a full metallic common battery party line. The line may have as many as forty stations, divided code ringing being used. As is well known, this means that the subscribers are signalled by means of code rings, part of the ringers being connected from one side of the line to ground, while the ringers at the other stations are connected from the other side of the line to ground. The line associated with line circuit #2 is a grounded local battery party line, and may have as many as twenty stations. The subscribers are signalled by means of code ringing. Line circuit #2 is similar to line circuit #1. It will be understood that various other types of lines may be connected to the C. A. X., such as individual lines and party lines with bridged ringers. Such lines are well known in the art and hence have not been shown in the drawings, but will be referred to more particularly later on in discussing the operation of the system.

Connections between the various subscribers' lines in the system and connections from a subscriber's line to an outgoing trunk are established by means of a number of finder connector links. One of these links is shown in Figs. 1 and 2 of the drawings. It comprises a finder switch, Fig. 1, which is indicated by the appropriate label, and a connector switch, Fig. 2, which is indicated by the label connector. The finder switch, Fig. 1, is preferably a rotary 50-point switch, while the connector switch, Fig. 2, is preferably a 100-line Strowger switch of the vertical and rotary type. Other types of switch, however, may of course be used. The link circuit also comprises a number of relays which are shown in Figs. 1 and 2, and a repeating coil which is shown in Fig. 2. It should be mentioned also that the connector has associated with it a small 10-point rotary switch CS which functions as a code selector for ringing purposes.

Common to all of the link circuits there is provided a finder distributor, which is shown in Fig. 3 of the drawings. This finder distributor comprises a ten-point rotary switch having four wipers and a number of relays for controlling the operation of the distributor switch and also for controlling the operation of the finders of the

finder connector links. The finder distributor also has associated with it a timer switch which is labelled TS in Fig. 3, and a pulse machine P.

The code ringing equipment is shown in Fig. 4 and comprises a code switch labelled CCS, together with a number of relays which are controlled thereby. This equipment is, of course, common to the finder connector links. Fig. 4 also shows an interrupter I, consisting of a number of relays, a ringing machine including the generator GEN, and a number of other relays whose functions will be pointed out hereinafter.

As mentioned hereinbefore, Fig. 5 shows a trunk circuit which may be used for connecting the C. A. X. in question with a distant manual exchange. At the manual end the trunk circuit terminates in a jack J, which has associated therewith the usual call signal lamp. At the other end, the line conductors of the trunk circuit extend to and terminate in a subscriber's line equipment which may be the same as one of the line equipments shown in Fig. 1.

The operation of the system will now be described, it being assumed for this purpose that the subscriber at station A on the party line associated with line circuit #1 desires to call the subscriber at station B on the line associated with line circuit #2. When the receiver is removed at station A, a bridge is closed across the line conductors 2 and 3 in the usual manner, and it follows that a circuit is completed for the double wound line relay 6, which is bridged across the line in series with the battery. Line relay 6 operates, and at armature 13 it connects ground to the private normal conductor 11, whereby the line is made busy in the banks of the connector switches. At armature 12 the line relay 6 connects the cut-off relay 5 to the third conductor 30 of the line circuit. This operation marks the line as calling in the banks of the finder switches, the other terminal of the cut-off relay 5 being connected to battery. Finally, the line relay 6 places ground on the starting conductor 50 at armature 11.

As a result of the grounding of start wire 50, a circuit is completed for the start relay 207 of the finder distributor, Fig. 3, the circuit extending by way of conductor 50, armature 231, winding of relay 207, armature 228, and winding of the stepping magnet 213, to battery. It should be noted at this time that relay 210 is normally energized. This relay may be termed an "all trunk busy" relay. It is held up over common conductor 254 by ground at all idle link circuits in multiple, so that this ground is not removed to permit the relay to fall back until all of the link circuits become busy. As a result of the closure of its circuit as pointed out above, relay 207 energizes and at armature 220 closes a pre-energizing circuit for the line relay 100 of the connector. This circuit extends from armature 220 by way of resistance 215, wiper 202, conductor 251, armature 89, conductor 55, contacts controlled by armature 124 of relay 104, Fig. 2, upper left hand winding of the repeating coil, contacts controlled by armature 120, and winding of line relay 100 to battery. The line relay 100 energizes over the above circuit and brings about circuit operations in the link circuit which result in the grounding of the release trunk conductor 57. These operations will be discussed more in detail later on.

As a further result of the energization of the start relay 207 in the finder distributor, a circuit

is completed for the slow-acting relay 206. A branch of this circuit extends by way of armature 214, wiper 203, and conductor 252 to the stepping magnet 54 of the finder switch, Fig. 1. On the closure of these parallel circuits, the relay 206 and the stepping magnet 54 both energize. Relay 206 prepares the finder test circuit at armature 218. The stepping magnet 54, upon energizing, places ground on conductor 255, thereby closing a circuit through the lower winding of the stepping relay 205. The said relay thereupon operates and breaks the circuit of the stepping magnet 54 at armature 214. Magnet 54 thereupon deenergizes, as a result of which the wipers of the finder are advanced one step. The circuit of the stepping relay 205 is broken at the same time and this relay accordingly falls back and again closes the circuit of the stepping magnet 54. The magnet and stepping relay, accordingly, continue to interact in this way and the finder switch wipers are driven around in the usual step by step manner in search of the calling line.

When the test wiper 52 reaches the marked test contact in its bank, the test circuit is completed over a path which extends from ground at armature 218, upper winding of the stepping relay 205, wiper 204, conductor 253, the lower winding of test relay 60, wiper 52, conductor 30, armature 12, armature 1, and winding of the cut-off relay 5, to battery. The closure of the above circuit holds relay 205 energized, so as to prevent further rotation of the finder switch, and also energizes the test relay 60 sufficiently to close its contact at armature 68. It is immaterial whether the cut-off relay 5 pulls up upon the initial closure of the circuit or not. When relay 60 closes contact 68, the relay thereby becomes locked to the grounded release trunk conductor 57. At the same time, the connection of ground to the test circuit at this point insures the full operation of the cut-off relay 5 of the subscriber's line circuit. The operation of the cut-off relay 5 disconnects the line relay 6 from in bridge of the line at armatures 14 and 10. The cut-off relay locks itself to the conductor 30 at armature 9 so that this circuit is maintained after the line relay 6 falls back. The cut-off relay 5 also closes a circuit for the slow-acting relay 4, and this relay energizes although its operation is of no particular effect at this time. Ground is removed from the start conductor 50 by the falling back of the line relay 6, or by the operation of relay 4.

Returning now to the test relay 60 of the finder, a holding circuit including the upper winding is obviously completed to conductor 57. At armatures 67 and 70, the two sides of the subscriber's line are extended by way of the line wipers 51 and 53, and the said armatures 67 and 70 to the talking conductors 55 and 56 of the link circuit. Conductor 56 is grounded at armature 166 of the connector cut-in relay 111. Conductor 55, as previously explained, extends to battery by way of the winding of the line relay 100. A circuit for the line relay 100 is therefore now completed over the calling subscriber's loop.

In addition to the foregoing, the test relay 60 connects ground to the conductor 250 at its armature 69. As a result of this operation a circuit is completed by way of conductor 250, wiper 201 of the finder distributor, armature 216, and winding of the stepping magnet 213, to battery. Stepping magnet 213, therefore, energizes, and at the interrupter contact of the magnet the circuit of the start conductor is broken. The start relay 207 thereupon falls back. As a result ground at 75

armature 220 is removed from the pre-energized circuit of the line relay 100 in the link circuit. Ground is maintained on this circuit, however, for a short time longer by means of armature 217 of the slow-acting relay 206 in order to insure that the calling subscriber's line will be connected through to hold the line relay up as has been described in the foregoing. The falling back of the start relay 207 also opens the circuit of the slow-acting relay 206, which upon falling back disconnects ground from the upper winding of the stepping relay 205. It will be understood that the latter relay was shunted by the connection of grounded release trunk conductor 57 to the test circuit at armature 68 of the test relay 60. This renders relay 205 slightly slow to fall back so that it does not deenergize to close the stepping circuit at armature 214 until the start relay 207 has deenergized. The falling back of slow-acting relay 206 also breaks the circuit of the stepping magnet 213 of the finder distributor at armature 216. This magnet therefore deenergizes and the wipers 201 to 204, inclusive, are advanced one step so that the distributor is associated with the next link circuit. The start relay 207 having deenergized, a test circuit is now completed which extends from the test wiper 201 by way of armature 219, armature 228, interrupter contacts of the stepping magnet 213, and the winding of the said magnet to battery. If the next link circuit is busy the contact engaged by wiper 201 will have ground on it and the magnet 213 will be momentarily operated to advance the wipers to the next link circuit, this operation continuing until an idle link circuit is found.

In further explanation of the way in which the link circuits are made busy, in connection with conductor 250 of the link circuit shown in Figs. 1 and 2, it will be noted that this conductor is grounded whenever the test relay 60 is energized. After the connector has been operated and if the test relay 60 should fall back, as upon release of the connection, conductor 250 is maintained grounded by way of the vertical off-normal springs VN¹. Thus conductor 250 is maintained grounded continuously from the seizure of the calling line until the link circuit is finally restored to normal by restoration of the connector. It should be stated also that the link circuit can be made artificially busy by operation of the busy key BK.

Attention will now be directed to the circuits of the link, Figs. 1 and 2, for the purpose of explaining more in detail the operations which ensue as a result of the energization of the line relay 100. Upon energizing, relay 100 completes a circuit for the lock-pulse relay 64 over the following path: from ground at armature 235 of relay 211, Fig. 3, by way of conductor 257, normally closed contacts controlled by armature 122 of relay 103, Fig. 2, armature 127 of relay 104, armature 83 of relay 66 and its back contact, armature 114 of the line relay 100, and winding of relay 64, to battery. Conductor 257 may be termed the "supervisory ground" conductor and supplies ground to numerous operating circuits of the link for a considerable portion of the time of its operation. For convenience this conductor and a number of ramifications thereof have been shown by means of alternate heavy and light lines, so as to avoid the necessity of tracing numerous circuits back to ground at armature 235 of relay 211. By illustrating this supervisory ground conductor and its branches in this manner, supervisory ground can be picked up at numerous points in

the link circuit, and the tracing of circuits is thereby much simplified.

Continuing with the operation, the lock-pulse relay 64 energizes when its circuit is completed by the line relay 100 and at armature 76 is connects supervisory ground to its circuit independent of the contacts of relays 66 and 104. Relay 64 also opens the impulsing circuit at armature 77, and at armature 75 supervisory ground is extended to the slow-acting release relay 65. Relay 65 thereupon pulls up and connects supervisory ground to the release trunk conductor 57. Conductor 57 is thus grounded, as briefly mentioned before, in order to hold up the test relay 60 and energize the cut-off relay 5 of the calling line. As a further result of the grounding of the release trunk conductor 57, a circuit is completed from said grounded conductor by way of contact 142 of relay 107 in parallel with contact 91 of relay 61, and thence by way of armature 126 of relay 104 and the winding of relay 66 to battery. Among other things, relay 66 extends supervisory ground by way of its armature 83 to the armature 115 of relay 100. This operation places the slow-acting release relay 65 under the joint control of the line relay 100 and the lock-pulse relay 64. A further result of the grounding of release trunk conductor 57 is the completing of a circuit which extends from said conductor 57 by way of the vertical off normal springs VN³ and the upper winding of slow-acting relay 106. Relay 106 energizes, and at armature 139 the impulse circuit is extended from the back contact of armature 77 of the lock-pulse relay 64 to the vertical magnet 180, preparatory to the receipt of impulses from the calling line. Relay 106 also operates its armature 138 and thereby connects dial tone to the upper talking conductor of the link in order to notify the calling subscriber that he can dial the called number.

The number of station B is 215. The first two digits, the digits 2 and 1, are determined by the fact that the line of station B is connected in the connector banks at the first set of contacts in the second level. This is clearly shown in the drawings. The third digit of the number depends on the code assigned to the desired substation B, and in this instance is arbitrarily assumed to be the digit 5.

When the subscriber at station A operates his calling device for the first digit 2, the line circuit is twice interrupted momentarily at the impulse springs of the calling device in the usual and well known manner. At the first interruption the line relay 100, Fig. 2, deenergizes and at armature 114 breaks the circuit of the lock-pulse relay 64. Relay 64 accordingly falls back and at armature 76 breaks its own locking circuit, so that when the line relay 100 is energized at the end of the first interruption the lock-pulse relay 64 will not pull up again forthwith. Lock-pulse relay 64 upon falling back also connects supervisory ground to the impulse circuit which extends by way of armature 77, armature 36, armature 139 and its front contact, and winding of the vertical magnet 180, to battery. The vertical magnet 180 accordingly energizes and steps the switch shaft carrying the wipers 182 to 185, inclusive, up one step. The vertical magnet also closes a circuit for relay 64 which extends from ground, contact 70 of vertical magnet, armature 114 of line relay 100, (which may be energized again by this time), and winding of relay 64 to battery. Relay 64 therefore again energizes, locks itself at armature 76, and breaks the vertical magnet circuit at ar-

mature 17. The vertical magnet now falls back preparatory to taking another step. On the next interruption received from the dial, the line relay 100 and the lock-pulse relay 64 operate as before 5 and the result is that another impulse is transmitted to the vertical magnet 180, thereby stepping the switch shaft up so that the wipers stand opposite the second level of bank contacts. At the end of the series of impulses relays 100 and 64 10 come to rest in energized position.

During the transmission of the series of impulses as just described, the release relay 65 is controlled jointly by the line relay 100 and the lock-pulse relay 64. Relay 65 is slow acting and 15 has to be maintained operated throughout the series of impulses. Since the operating times of relays 100 and 64 overlap to a certain extent, the maintaining of relay 64 in energized position is more certainly assured than if the relay were 20 controlled by the line relay alone.

At the first upward movement of the connector switch shaft, the vertical off normal springs are shifted in the usual manner. The vertical off normal springs VN¹ have already been referred 25 to. The off normal springs VN² prepare a circuit for the release magnet 186, which, however, is open at this time at armature 86 of relay 66. The off normal springs VN³ break the circuit of the slow-acting relay 106. This relay, however, is 30 maintained energized in parallel with the vertical magnet 180 during the first series of impulses. At the end of the first series of impulses relay 106 falls back and at armature 139 the impulsing circuit is transferred to the rotary magnet 181.

35 The calling subscriber may now dial the second digit 1 of the called number. This operation produces a single interruption in the subscriber's loop and causes the line relay 100 to deenergize momentarily a single time. As described in the foregoing, the lock-pulse relay 64 is controlled by the line relay 100 and transmits an impulse this time to the rotary magnet 181. The rotary magnet operates responsive to this impulse and steps the switch shaft around one step so that the wipers 40 of the switch move in on to the first set of contacts in the second level.

During the transmission of impulses to the rotary magnet, the slow-acting relay 108 is energized in parallel with the magnet and at armature 149 it completes a circuit which extends from said armature by way of armature 144, armature 164, the winding of relay 109, to battery. Relays 108 and 109 are both slow-acting relays and they remain energized during the rotary operation of 45 the switch. It should be noted at this time that in its energized position relay 109 extends ground from the release trunk conductor 51 by way of armature 152, to the contact springs of the rotary magnet 181. These contact springs have the function of re-operating the lock-pulse relay 64, as described in connection with the vertical magnet 180. The circuit described is employed rather than a circuit extending direct to ground so as to insure that the relays 108 and 109 will become 50 fully energized before the first pulse is terminated.

At the end of the rotary movement of the switch, relay 108 falls back, and breaks the energizing circuit for relay 109. This latter relay, when it first energized, prepared a circuit at armature 154 for operating relay 102. Accordingly when ground is removed from the circuit of relay 109, relays 102 and 109 are energized in series over a circuit which extends from ground at the busy key by way of armature 64 of relay 60 and vertical off normal springs VN¹, winding of relay 55

102, armature 116, contacts controlled by armature 117, armature 154, and winding of relay 109, to battery. Upon energizing over the above circuit, relay 102 locks itself at armature 117 independent of relay 109. Relay 109 thereupon de-energizes. The operation and locking up of relay 102 is effective at this time to transfer the impulse circuit at armature 119 from the rotary magnet 181 of the connector switch to the stepping magnet 192 of the code selector CS. 10

The connector has now been set on the desired called line, but the line has not been tested as yet. This operation is deferred until the code selecting digit is dialled. When the calling subscriber dials the last digit 5 of the number, five 15 interruptions are produced in the loop circuit and relays 100 and 64 respond in the manner already described to transmit five impulses to the stepping magnet 192. As a result the wipers 180 and 181 are advanced five steps so that they come to 20 rest on the fifth contacts of their respective banks. Relay 188 is energized in parallel with stepping magnet 192 and at armature 148 closes a circuit for the slow-acting relay 108. These two relays accordingly are maintained in operated position 25 throughout the series of impulses transmitted to the stepping magnet 192. On the first step of the code selecting switch CS, the rotary off normal springs RN are closed, and a circuit is completed for relay 113. There is a resistance in this circuit 30 and relay 113 only operates part way, sufficient to shift its armatures 178 and 177. Armature 116, however, is not operated at this time. At armature 177, the release circuit is transferred from release magnet 186 of the connector switch to 35 release magnet 193 of the code selector. At armature 178 the test wiper 183 of the connector is connected up.

Since relays 108 and 109 are operated during the rotation of the code selector CS, a circuit for 40 the test relay 105 is prepared at armature 153 of relay 109. This circuit is completed at armature 148 of relay 108 when this relay falls back at the end of the series of impulses to stepping magnet 192. The operation now depends on 45 whether the called line is busy or idle. If the called line is busy there will be a ground potential on the test contact engaged by wiper 183 and the test relay 105 will pull up over a circuit which extends from the grounded test contact by way 50 of test wiper 183, armature 178, armature 153 and front contact (slow-acting relay 109 is still energized), armature 148, the winding of relay 105, to battery. Relay 105 accordingly energizes and prepares a locking circuit for itself at armature 55 132. The slow-acting relay 109 deenergizes now and the locking circuit is completed from the grounded conductor 51 by way of the armature 132, contacts controlled by armature 153, armature 148, and winding of relay 105 to battery. As 60 a further result of its operation relay 105 opens the circuit of the cut-in relay 111 at armature 135, and at armature 136 the impulse circuit is transferred on to the conductor which leads to armature 114 of the line relay. The latter pre- 65 caution is necessary in order to provide a circuit for re-operating the lock-pulse relay 64 in the event that the calling party should happen to dial a digit or accidentally open his line circuit momentarily while connected to a busy line. Were it not for this provision the lock-pulse relay 64 would fall back and could not again become operated because there is no stepping magnet being controlled at this time. If permitted to remain 70 75

deenergized the lock-pulse relay 64 would transmit ground by way of its armature 76, armature 84, and armature 134 of the now energized test relay 105 to the test wiper 183. This would ground the private normal conductor of the busy line and would prevent such line from disconnecting. The arrangement described insures that when the lock-pulse relay 64 falls back responsive to a momentary interruption of the line it will immediately close a fresh circuit for itself by way of armature 136 of the test relay 105 and armature 114 of the line relay 100.

A further result of the operation of the test relay 105 is the placing of a busy tone on the talking circuit at armature 130. This notifies the calling subscriber that the desired line is busy and he will accordingly hang up his receiver. Upon the replacement of the receiver the line relay 100 is deenergized, followed by the falling back of relay 64. Since relay 100 remains back, relay 64 cannot close an energizing circuit for itself and both these relays remain deenergized. The release relay 65 therefore falls back and removes ground on the release trunk conductor 51. This allows the test relay 60 to fall back and also deenergizes the cut-off relay 5 of the calling line. The removal of ground from the release trunk conductor 51 also permits relay 66 to fall back and close the release circuit which now extends to the release magnet 193 of the code selector. The code selector CS is thereupon restored to normal and upon reaching normal position the off-normal springs RN are opened. This causes relay 113 to fall back and transfer the release circuit to the release magnet 186 of the connector. The connector is thereupon restored in the usual manner. Test relay 105 is, of course, restored when ground is removed from the release trunk conductor 51.

It will be assumed now that the called line was found idle. Under this condition, there will be no ground on the test contact engaged by the test wiper 183, and when the circuit of the test relay 105 is completed by the deenergization of relay 108 said test relay will not pull up. Shortly after relay 108 falls back, relay 109 falls back, and a circuit is completed for the cut-in relay 111. This circuit may be traced from the supervisory ground conductor by way of armature 80 of the release relay 65, armature 135, upper winding of cut-in relay 111, armature 153, armature 178, test wiper 183, test contact engaged thereby, conductor 26, upper armature of the line relay 24 of the called line, Fig. 1, and winding of the cut-off relay 23 to battery. Upon the closure of this circuit the cut-in relay 111 and the cut-off relay 23 of the called line are energized in series. The cut-off relay 23, upon operating, disconnects the line relay 24 from the called line. The cut-in relay 111, upon energizing, connects up the line wipers 182 and 185 at armatures 158 and 168, respectively. At armature 167 the impulse circuit to the magnet 192 is opened. At armature 165 supervisory ground is connected to the test wiper 183, thereby short circuiting the upper winding of relay 111. Relay 111, however, locks itself energized at armature 161, by means of which a circuit for the lower winding of relay 111 is completed to ground at armature 81 of relay 66. Relay 111 also breaks the circuit of relay 109 at armature 164, and at armature 163 it prepares a circuit for the pick-up relay 112. A circuit for the ringing relay 110 is also prepared at armature 162, likewise a circuit for relay 170 at armature 159.

The connector is now ready to ring the called subscriber. When the cut-in relay 111 pulls up it grounds the start conductor 307 for starting the ringing equipment shown in Fig. 4. The detailed operation of this equipment will not be gone into at this time. For the purposes of the present description, it will be sufficient to state that ringing current is supplied over conductor 308, while intermittent ground impulses in code are transmitted over conductors such as 331, 332, etc., to the banks of the code selector CS. If the ringing equipment is in normal position when the cut-in relay 111 pulls up, a circuit is immediately completed over the pick-up conductor 306 for the pick-up relay 112. If the ringing equipment is not in normal position, this circuit is completed by wiper 305 of the code switch CCS when it reaches the first contact in its bank, at the beginning of a code cycle. Upon energizing, the pick-up relay 112 locks itself to ground at armature 174. In addition relay 112 grounds the lower line wiper 185 at armature 175. The purpose of this is to complete a return path for ringing current in case the line about to the signalled has full metallic ringing. Finally, relay 112 completes a circuit for the ringing relay 110 at armature 173. Wiper 191 is standing on the fifth contact in its associated bank, so that now a code comprising two spaced ground impulses is transmitted from conductor 338 by way of the fifth contact in the bank of wiper 191, the said wiper 191, armature 176, armature 173, upper winding of ringing relay 110, armature 162, interrupter contact of the rotary magnet 181, and lower winding of ringing relay 110 to battery. The ringing relay 110 is thereby operated in accordance with the code 1-1.

Each time the ringing relay operates it closes a circuit at armature 155 whereby ringing current from the conductor 308 is transmitted to the wiper 182 of the connector and thence by way of conductor 25 to the line conductor 20 of the called line, Fig. 1. From line conductor 20 the ringing current flows through all the ringers on the line in parallel to ground. The ringers are all actuated therefore in accordance with the code 1-1, and since this is the code assigned to station B the subscriber at that station is notified to answer his telephone. Each time that relay 110 pulls up it also closes a circuit for relay 170. At its left hand armature 169 relay 170 connects ringing current by way of the small condenser to the upper conductor of the talking circuit so as to transmit a ringing tone to the calling subscriber. This informs the calling subscriber that the called line is being signalled. Relay 170 also connects a shunt around relay 63 at its right hand armature 172, and this shunt is maintained for a short interval after the ringing relay 110 falls back, relay 170 being slightly slow acting. The purpose of this shunt is to provide a non-inductive path for discharging the condensers on the line each time the ringing relay 110 deenergizes, so as to eliminate any chance of falsely operating relay 63.

When the called subscriber at station B removes his receiver to answer the telephone, a conductive circuit is completed from ground by way of the secondary winding of the induction coil and the receiver to the line conductor 20. At the first silent interval this results in the completion of a circuit for relay 63 which extends by way of the conductor 20, normal con-

ductor 25, wiper 183, armature 158, armature 155 (ringing relay 110 being deenergized), upper right hand winding of the repeating coil, armature 74, and the winding of relay 63 to battery. Upon energizing, relay 63 closes at its armature 13 a circuit for relay 103. Upon energizing, relay 103 at its armature 119 closes a circuit for the ring cut-off relay 107. Upon energizing, the ring cut-off relay 107 locks itself at armature 141. At armature 140, relay 107 closes the talking circuit by completing the connection between the two right hand windings of the repeating coil. At armature 143, relay 107 breaks the circuit of the pick-up relay 112, which thereupon falls back and breaks the circuit of the ringing relay 110 at armature 173. At armature 144 relay 107 breaks the circuit of relay 109 and also prepares a circuit for the lock-pulse relay 64. This latter circuit is effective to reenergize the lock-pulse relay in the event that the calling subscriber should dial an additional digit or in some way accidentally open his line circuit momentarily. At armature 146 relay 107 disconnects ground from the start conductor 307, so that the ringing equipment will be brought to rest in the event that no other connectors are in use.

Returning now to relay 103, at armature 122 this relay disconnects the supervisory ground conductor 257 and replaces it by direct ground. Another result of the operation of relay 103 is the reversal of the line conductors 55 and 56 incoming to the connector as regards their connection to battery and ground in the connector, thereby reversing the direction of current flow over the calling line. In further explanation of this operation, it should be pointed out that when the cut-in relay 111 of the connector operates (as previously described) it disconnects ground at armature 166 from the lower line conductor 56 and thereby removes the short circuit from the winding of relay 101. This relay accordingly energizes over the calling line in series with relay 100. Upon energizing, relay 101 breaks the circuit of relay 102 at armature 116. Relay 102 thereupon deenergizes. Since relay 102 is deenergized, the operation of relay 103 will reverse the current in the calling line, as stated. However if a grounded line, such as the line having the 50 substation B, had been calling, the lower line conductor 56 would have remained grounded at the line circuit so that the removal of ground at armature 166 of the cut-in relay 111 would have had no effect. Relay 101 would therefore have remained short circuited, relay 102 would have remained energized, and the operation of relay 103, therefore, would have been ineffective. The arrangement including relay 102, therefore, provides for discriminating between metallic circuit 55 lines and grounded lines, the relay 103 being effective to reverse the connections of the relays 100 and 101 to metallic lines, but being ineffective to reverse such connections in the case of a grounded line. The reversal is of no utility in 60 the connection which has just been described, that is, when the line to which substation A is connected is the calling line. This is a standard operation, however, and is of utility, for example, in the case of a calling line which is equipped 65 with a pay-station. The system illustrated may well include several pay-station lines and the provisions for reversing the current are therefore essential. It is also required on calls over trunk lines such as the one disclosed in Fig. 5, as will 70 be mentioned later on.

The required connection has now been completed. The calling line is supplied with talking current through the windings of the relays 100 and 101 and the left hand windings of the repeating coil. The called line is a local battery line and station B therefore is not supplied with talking current from the connector. A talking circuit is, however, completed from ground at the line equipment by way of normal conductor 28, wiper 185, the two right hand windings of the repeating coil in series, and wiper 182 to the line conductor 20 by way of normal conductor 25. The talking circuit has been drawn in by means of heavy lines and will therefore be readily traced. 15

When the called subscriber hangs up his receiver relays 63 and 103 are deenergized. When the calling subscriber hangs up his receiver relays 100 and 101 are deenergized. Relay 100 breaks the circuit of relay 64, and the release relay 65 accordingly falls back after a short interval. The connection is thereupon released in substantially the same manner as has been previously described in the case of release from a busy line.

The operation of the apparatus shown in Fig. 4 will now be described in detail, without reference to any particular call. The start conductor 307 is common to all the link circuits, that is, it extends to contacts on the cut-in relays such as relay 111 of all the connectors. When any connector establishes connection with a called line and the cut-in relay, such as 111, operates, ground is connected to the start conductor 307. As a result a circuit is completed for the relay 315. Relay 315 closes a circuit for the motor of the motor generator set at its armature 320. This starts the motor generator set or ringing machine in operation with the result that ringing current is generated and projected out over conductor 308. This conductor extends to all of the connectors for the purpose of supplying ringing current. 25

The operation of armature 320 of relay 315 also extends ground to the relay interrupter comprising relays 311, 312, and 313. Relay 311 therefore energizes and removes a shunt circuit from relay 312, which then energizes also. Relay 312 then removes the shunt circuit from relay 313, so as to permit it to energize. The latter relay short circuits relay 311 and causes it to fall back, whereupon relays 312 and 313 are successively short circuited and deenergized. The latter relay then removes the shunt circuit from relay 311 and permits it to pull up again. These operations continue as long as ground is supplied, with the result that impulses are transmitted over conductors 330 and 329. Conductor 330 is connected in multiple to wipers 301 to 304, inclusive, of the coding switch CCS, while conductor 329 extends to the stepping magnet 309 of the coding switch. 30 The magnet 309 is therefore intermittently operated to advance the wipers 301 to 305, inclusive, step by step over their associated banks. The operation of the coding switch in producing various codes of ground impulses on the code ring- 35 conductors will first be described.

Considering wiper 301 it will be observed that the fifth and seventh contacts of its bank are connected to master code conductor 341. As the switch is advanced step by step over its bank contacts wiper 301 will eventually rest for a moment on the fifth bank contact. When the next impulse is delivered to conductor 330 this bank contact accordingly becomes grounded and a ground impulse is transmitted to master code conductor 75

341. At the same time, approximately, an impulse is delivered to the stepping magnet 309. After a moment the interrupter relays deenergize and ground is removed from conductors 330 and 329, the removal of ground from the latter conductor permitting the switch to advance its wipers to the next set of contacts. The operation thus continues, and when wiper 301 rests on the seventh contact in its bank another ground impulse is delivered to the master code conductor 341. It will be seen, therefore, that in one complete cycle of operation of the code switch two spaced ground impulses will be delivered to the master code conductor 341.

15 In the case of wiper 302, it will be clearly seen on inspection that this wiper during the same cycle of operations will deliver two ground impulses to the master code conductor 342 from the fourth and fifth contacts of its bank and 20 two additional ground impulses from the seventh and eighth contacts. Also it will be seen that wiper 203 will deliver three ground impulses to master code conductor 343 from the third, fourth, and fifth contacts of its bank, followed by three 25 more ground impulses from the seventh, eighth, and ninth contacts in its bank. Wiper 304 is the 4-4 code wiper and delivers in an obvious manner four ground impulses to master code conductor 344 followed by four more ground impulses.

30 From the foregoing it will be understood readily enough that the code ringing conductor 335, which is the ringing conductor for the 4-4 code, can be connected directly to the master code conductor 344, as shown in the drawing. Similarly the code ringing conductors 336, 337, and 338 are directly connected to the master code conductors 343, 342, and 341, respectively.

40 In order to produce the combination codes in which the number of rings in the two halves of the code are unequal, the relays 318 and 319 are employed. Relay 318 is energized over wiper 301 in the first position of the code switch CCS. This relay locks to the grounded start conductor 307. 45 When wiper 301 of the coding switch CCS arrives at the sixth contact in its bank a circuit is completed for relay 318. This relay operates and breaks the locking circuit of relay 319. The latter relay accordingly falls back and a locking 50 circuit is closed for relay 318. When wiper 301 again arrives at the first contact of its bank relay 319 is again energized and relay 318 is unlocked. Relay 319 is therefore energized while the wipers of the coding switch are traversing the 55 contacts in the first half of the bank, while relay 318 is energized while the wipers are traversing the contacts in the second half of the bank.

60 From the foregoing it will be easy to deduce the codes which are transmitted over the remaining code ringing conductors. In the case of conductors 331, for instance, the code transmitted over this conductor consists of four short rings followed by three short rings. During the first half of the code switch cycle the conductor 331 is connected by relay 319 to master code conductor 344, from which it receives four ground impulses, while during the second half of the cycle the code switch conductor 331 is connected by relay 318 to master code conductor 343 from 65 which it receives three ground impulses. Thus the code transmitted over the ringing conductor 341 is 4-3.

70 In the same way it will be seen that code ringing conductor 332 receives a code consisting of four impulses followed by two impulses. By way

of further example, conductor 333 receives three impulses followed by four impulses, while conductor 334 receives four impulses followed by two impulses. It will be unnecessary to consider in detail the remaining code ringing conductors as the ground impulse combinations transmitted over them will be apparent from the drawings.

75 It remains to consider the special direct line ringing conductor 339, which is provided for ringing individual lines and any other situations where a single long ring is desired. This conductor extends to contacts of relay 319 so that during the first half of the cycle of operation of the coding switch CCS it is connected down to a contact on relay 310. The relay 310 is energized continuously while grounded wiper 305 is in engagement with the second, third, and fourth contacts of its bank. Thus, by the operation of relay 310 a relatively long application of ground is made to conductor 339.

10 Wiper 305 also controls the application of ground to the pick-up conductor 306. If the coding switch CCS is in its normal position the conductor 306 is grounded, so that when a connector is cut in on a called line the pick-up relay, such as relay 112, is energized immediately. However, if the code switch should already be in operation due to the fact that a subscriber is being signalled from another connector switch, the energization of the pick-up relay will have to 15 await the grounding of conductor 306 by wiper 305 when the coding switch arrives at its first position. The use of the pick-up conductor is well understood, its function being to insure that a mutilated code will not be applied to a called 20 line, as would happen if a connector were permitted to start ringing with the coding switch in any random position.

25 The operation of the relays associated with the relay 315 will now be more particularly described. When relay 315 is energized it closes a circuit for a signal lamp in series with an alarm relay 330. At the same time a circuit is prepared for relay 316, which is completed by wiper 301 of the coding switch when the wiper reaches the 30 second contact in its bank. On energizing, relay 316 locks itself independent of wiper 301, and closes a circuit for the alternating current relay 314. If the ringing machine is started up all 35 right and is producing ringing current, relay 314 will operate, preparing a circuit at armature 326 for relay 317. When the wiper 301 of the code switch CCS arrives at the last contact in its bank the circuit for relay 317 is completed and this relay energizes, locking itself to the grounded 40 start conductor 307. Relay 317 opens the circuit of relay 316 at armature 323, and at armature 327 it breaks the circuit of the alarm relay 330. Relay 316 on falling back, breaks the circuit of relay 314, which accordingly deenergizes also. 45 As a result relay 317 remains energized until the ground is removed from start conductor 307.

50 The purpose of the foregoing operation is to test the starting of the coding switch CCS and the ringing machine. It will be obvious that if the coding switch failed to start the described operations could not be completed, nor could they be completed if the ringing machine failed to produce ringing current. The circuit of the alarm relay 330 would therefore remain closed 55 and an alarm would be transmitted to the distant exchange where the wire-chief, or other official charged with the duty of maintaining the equipment in operation, has his station. The 60 circuits by which the alarm is transmitted from 65 70 75

no part of this invention and hence have not been shown.

When ground is removed from conductor 307, relays 315 and 317 fall back. Relay 315 stops the ringing machine and the interrupter I by removing ground at armature 320. Relay 315 also closes a circuit at armature 321 for restoring the coding switch CCS to normal. These contacts close a self interrupted circuit for the stepping magnet 309 in an obvious manner, which is broken by wiper 305 when the switch reaches normal.

In the foregoing description the dialling circuit in the connector has been only briefly described, as it was considered that it would be inconvenient to interrupt the explanation in order to discuss it in detail. Some further consideration will therefore be given to the dialling arrangements in order to point out their advantages somewhat more fully. It has already been stated that the system herein shown and described is intended for use in a small community where as a rule various types of lines will be found in use. The dialling conditions accordingly will vary between wide limits. Some of the lines may not be very well insulated and there will be on such lines, therefore, a considerable leak to ground. The bridged ringers on the party lines, whether bridged across the line or to ground, impose a condition on the line relay which is somewhat similar to that imposed by a leaky line. The line relay will tend to fall back slowly and to energize quickly, with the result that very short impulses will be produced at its back contact during a series of dialling impulses. There may be other lines in the system which are relatively long and of high resistance, and if the insulation on these lines is good an entirely different condition will be imposed on the line relay. When dialling impulses from such a line are being received the line relay will tend to fall back quickly and pull up slowly, resulting in long impulses at its back contact and very short impulses at its front contact. The improved dialling circuits which are herein shown and described meet these conditions with a maximum of efficiency. The tests have shown that satisfactory dialling can take place with these circuits over a line which has a leak to ground which is as low as 3500 ohms, and such line may at the same time have as many as twenty stations on it with their ringers either bridged across the line or bridged from the same side of the line to ground. The same connector as used in the foregoing will also operate satisfactorily on a long line having substantially no leak to ground and as high a resistance in the loop as 1200 ohms. The arrangement by which these results are accomplished will be pointed out somewhat more in particular.

To begin with, the line relay 100 is given a very stiff adjustment, that is, the contact springs which correspond to armatures 114 and 115 are adjusted very stiffly so that the relay will be sure to fall back each time that its circuit is interrupted even though dialling is taking place over a line which has the maximum leak to ground. It should be stated, however, that the adjustment is made only stiff enough to insure that each time the line relay circuit is interrupted the contact will be broken at armature 114. The special lock-pulse scheme which is included makes it immaterial whether armature 115 makes on its back contact or not. The lock-pulse arrangement includes a relay 64, which is dropped back every time the line relay

100 opens its contact 114. Relay 64 on dropping back opens its own locking circuit and closes the circuit for the stepping magnet such as 180. This insures that the stepping magnet will be energized fully each time relay 64 drops back, because the latter relay cannot pull up again until the stepping magnet operates fully. These circuits have been gone over before, and hence it will be unnecessary to trace them in detail.

The lock-pulse arrangement for securing a more positive delivery of impulses to a stepping magnet by a line relay is not broadly new. In one such arrangement which is well known, the line relay delivers impulses to the stepping magnet at its back contact. In parallel with the stepping magnet is a quick acting lock-pulse relay which pulls up at the beginning of the impulses and connects a locking ground to the impulse conductor so that the relay is maintained energized and the full operation of the magnet is insured. The magnet on completely operating then disconnects this ground so that it and the lock-pulse relay can fall back. This arrangement, it will be seen, depends on the quick energization of a lock-pulse relay, the theory being that a relay can be made to energize more quickly than the stepping magnet. The present arrangement, however, is much more desirable than the one described. The present arrangement depends on the falling back of a relay such as 64 upon the opening of contacts at the line relay. This arrangement has an advantage for several reasons. In the first place the time which is required for a relay to fall back is less than the time which is required for a relay to pull up. Consequently, a relay such as 64 will fall back quicker than the lock-pulse relay will pull up in the prior known arrangement. In the second place, when a lock-pulse relay is used like relay 64, which falls back to transmit impulses to the stepping magnet, it permits the control of the relay to be exercised over a front or make contact on the line relay instead of at a back contact. In deenergizing, the line relay of course breaks its front contact before it closes its back contact, so that here again a considerable advantage is presented. A close observation of the line relay 100 when dialling is taking place over a leaky line shows that the line relay barely separates its front contact at armature 114 with each interruption of the circuit and never closes the back contact at armature 115 at all.

As stated hereinbefore, an altogether different condition is imposed on the line relay when dialling is taking place over a high resistance line. Under these conditions, the line relay will tend to fall back quickly and will have difficulty in pulling up completely each time the circuit is closed between interruptions. In order to assist the line relay in operating under these conditions, a priming leak resistance 87 is provided. When the line relay falls back a circuit is completed from ground by way of armature 115 and its back contact, armature 79, resistance 87, and the winding of the line relay 100 to battery. This circuit is effective only under the conditions mentioned, that is, when the line relay fully deenergizes on each interruption of its circuit. It provides a circuit for partially energizing the line relay so that each time the loop circuit is closed at the calling device the relay can respond with the necessary speed.

It will not be necessary to consider the operation of the system when calls are made from other lines than the line of station A, except in a very general way. It will be clear that all of the full metallic lines in the system, whether individual

5   Lines or party lines, operate in exactly the same way as has been described in the case of the line of station A in so far as initiating calls is concerned and operating a finder connector link to 5 set up a connection. In the case of a grounded line such as the line of station B, the operations are substantially the same also, the only thing which needs to be considered being the different circuits which are involved because of the fact 10 that the stations on the line are bridged from a single line conductor to ground.

When the station B is calling for instance, the removal of the receiver grounds the line conductor 20 through the telephone instrument and operates the line relay 24. This starts the finder switch of an idle link circuit in the usual way. Assuming that the finder link circuit shown in the drawings is used, when the finder locates the calling line the wiper 51 will make connection 20 with the line conductor 20, while the wiper 53 will make connection with the conductor 21. This conductor in the case of a grounded line is connected to ground as shown in the drawings. When the subscriber dials the line relay 100 is 25 controlled over a grounded circuit which does not differ materially from the circuit over which this relay was controlled in the case of a call initiated at the line of substation A. In that case, it will be recalled, the lower line conductor 3 is connected through to link talking conductor 56 which is grounded at the connector throughout the dialling operation. In the case of the line of station B the circuit is grounded at the substation and consequently the dialling circuit will have a little 30 less resistance than in the other case. When the connection is completed the talking circuit will extend over the heavy talking conductors. It will be observed that this talking circuit includes both of the left hand windings of the repeating 35 coil in the usual manner, the lower terminal of the lower winding being connected by way of talking circuit conductors 56 and 21 to ground at the line circuit. Since the telephone instrument at station B is connected between the line conductor 20 and ground, a complete path will 40 exist over which conversation may be held.

It will be convenient now to explain how a subscriber such as the subscriber at station A calls another subscriber on his own line. This is what 50 is known as a "revertive call". It will be assumed that the desired station is station C, the number of which is 622.

When the receiver is removed at station A the same operations take place as have been heretofore described, with the result that the calling line is picked up by the finder switch of a finder connector link. Assuming that the link shown in the drawings is used, the finder switch will establish connection to the calling line as previous 60

65   ly described and circuits will be completed automatically for placing the connector under the control of the calling dial. When the first digit 6 of the desired number is called the connector wipers are stepped up to the sixth level in their respective banks. Following this the second digit

70   2 of the called number of dialled, with the result that the connector wipers are rotated two steps so that they come to rest on the second set of bank contacts in the sixth level. The subscriber now dials the last digit 2 of the number, causing the code selector CS to advance its wipers two steps. Following the operation of the code selector switch CS, the called line is tested in the 75 manner hereinbefore described, and of course it

is found to be busy. This, it will be understood, is because the called line is also the calling line.

Upon receiving the busy signal, the calling subscriber hangs up his receiver. The subscribers on party lines have special instructions and such a subscriber knows that when he calls a party on his own line he can expect to get a busy signal and that the proper procedure in such a case is to hang up his receiver and wait a sufficient length of time for the signalling operation to take place.

When the receiver is replaced at station A line relay 100 falls back, followed by the falling back of relay 64. Accordingly, the slow acting release relay 65 is deenergized an instant later. Relay 15 20 65 on deenergizing removes ground from the release trunk conductor 57 at its armature 78, but prior to this a fresh ground has been connected up in a manner which will now be explained. When relay 64 falls back it closes a circuit which extends from supervisory ground by way of armature 76, armature 84, armature 134 of the busy relay 105, and thence to the test wiper 183. The test wiper is now in engagement with a test contact to which the private normal conductor 17 is 25 connected so that ground is therefore extended by way of conductor 17, back contact of armature 13 of the line relay 6, Fig. 1, armature 9 of the cut-off relay 5, conductor 30, test wiper 52, and armature 66 to conductor 57 of the link circuit. Thus ground is maintained on conductor 57 30 to hold relays 5, 60, and 66 energized so as to maintain the connection.

When the release relay 65 falls back it completes a circuit at the back contact of its armature 78 which extends from the grounded conductor 57 by way of armature 82 and armature 133 to the relay 61, which thereupon energizes.

Relay 61 closes a locking circuit for itself at armature 92, and opens the heavy talking conductors 40 55 and 56 at armatures 89 and 93, respectively. In addition, relay 61 opens a point in the circuit of relay 66 at armature 91. Relay 66 is, however, held energized for the time being by way of armature 142 of relay 107. Finally relay 61 closes a 45 circuit at armature 90 which extends through the lower winding of the cut-in relay 111 to battery. Relay 111 thereupon energizes and brings about generally the same results as were accomplished in the case of the connection which was previously described. Among other things, relay 111 50 grounds the start conductor 307 so that the ringing machine is started up and the proper ringing current is transmitted out over the called line. This operation will be described in so far as is 55 necessary in order to point out the operation of the connector in shifting the wipers of the code selector CS.

It will be recalled that in this instance the wipers of the connector have been raised to the 60 sixth level. At the sixth level the shaft springs or level off-normal springs LN³ are closed by a cam on the connector shaft. These springs operate only on the sixth level. With the springs LN³ closed, the resistance in the circuit of relay 113 65 is short circuited, so that when the code selector CS is stepped off normal relay 113 completely energizes, and operates its armature 176 as well as its armatures 178 and 177. By the operation of armature 176 the upper wiper 190 of the code selector is substituted for the lower wiper 191.

The purpose of this arrangement will be readily understood. The code selector CS is only a ten-point switch and without some special arrange- 70 75

ment, therefore, it would only serve to select from ten different codes. In the present system, however, it is assumed that there will be at least a few large party lines which require twenty codes.

5 These party lines are multiplied in two different levels in the bank of the connector. The line of station A, for instance, is not only multiplied in the third level of the connector banks, but it is also multiplied in the sixth level. The line is connected with just the same regardless of which level is called, but when the line is called by way of the third level wiper 191 of the code selector is used whereas if the line is called by way of the sixth level, wiper 190 of the code selector will be used. This doubles the capacity of the code selector and makes it possible to use twenty codes.

10 While on this subject, it may be well to digress a little further and call attention to the arrangement which is made for enabling as many as forty parties on a line to be signalled. The line of station A is connected up as a forty-party line. As described in the above paragraph the line is multiplied in the first contact set of the third level and also in the second contact set of the sixth level, which provides for signalling twenty parties on the line. That is, twenty different codes may be selected by the code selector CS and twenty parties corresponding to these codes may therefore be placed on the line. These twenty parties all have their grounded ringers connected to the upper line conductor 2. Normal conductor 16 is connected to conductor 2 and at the other end is multiplied to bank contacts in the third level and the sixth level which are engaged by the active wiper 182 of the connector. Wiper 182 of the connector is the wiper over which ringing current is transmitted. Now, there may be twenty additional stations connected with the line which have their ringers connected between line conductor 3 and ground. In order to enable these twenty subscribers to be signalled two additional sets of bank contacts are assigned at the connector. As shown in the drawings, these additional sets of bank contacts are the first set in the fourth level and the third set in the sixth level. The normal conductors 16 and 19 are connected up to these two additional set of bank contacts reversed. That is, normal conductor 19 which is connected to conductor 3 at one end is connected at the other end to contacts in the fourth and sixth levels which are accessible to wiper 183 so as to provide for transmitting ringing current over the lower line conductor 3 instead of over the upper line conductor 2. It is assumed that ordinarily one level such as the sixth level, which is assigned for ringing those party lines which have a large number of subscribers, will be sufficient to take care of all the lines of this character that there are. However, if this is not the case, an additional level, such as the seventh level, could also be assigned for this purpose and the level off normal springs LN³ would then be constructed so as to close on both the sixth and seventh levels.

65 Returning now to the point where the description was left off, when the ringing equipment was started by the application of ground to conductor 307, the code switch CCS transmits ground impulses over the several code conductors as has been previously described. The code conductor 360 is the one which is concerned in the present connection, as this is the conductor which is selected by wiper 190 of the code selector CS. The code conductor 360 is the conductor for the 2-4 code, and accordingly it receives two ground

impulses followed by four ground impulses. These impulses operate the ringing relay 110 in the manner heretofore described and the relay transmits ringing current over wiper 182, normal conductor 16, and conductor 2 of the line in the proper manner to signal the subscriber at station C. It is assumed that station C is the station to which the code 2-4 is assigned. It should be mentioned at this point that during the signalling operation relay 170 breaks the circuit of the busy lead at the back contact of armature 169 each time ringing current is applied to the called line. This is to prevent the ringing current from backing up on the busy lead, which may at this time be connected up in another connector switch. This provision is only useful on a reverting call, since it is only on a call of this kind that the busy lead is connected up during the ringing operation, this being due to the fact that in a reverting call the busy relay 105 is energized.

20 When the called subscriber at station C answers his telephone, the removal of the receiver closes a circuit in the previously described manner for relay 63. This relay pulls up and closes a circuit for relay 103. The latter relay on energizing 25 closes a circuit for relay 107, all as previously described. Relay 107 upon energizing opens the circuit of relay 66 at armature 142. It will be recalled that it was previously pointed out that the energization of relay 61 opened one point in the 30 circuit of relay 66. On relay 107 operating to open the second point in the circuit of this relay at armature 142, relay 66 falls back. The de-energization of relay 66 results in the release of the connector switch. Ground is removed from the circuit of the wiper cut-in relay at armature 81, and at armature 84 ground is removed from the test wiper 183 and therefore from the private normal conductor 17 and the release trunk conductor 51. Also at armature 86 the circuit of the 40 release magnet 193 is completed. It will be seen, therefore, that as a result of the falling back of relay 66 the link circuit is released.

45 Considering now the effect at the line circuit, when ground is removed from the private normal conductor 17 the cut-off relay 5 falls back. This connects up the line relay 6, which promptly energizes over the line, since the subscriber at station C has his receiver off. The falling back of the cut-off relay 5 opens the circuit of relay 50 4, but this relay is slow acting and it is held by the line relay 6 over a circuit which includes armatures 11 and 8. Relay 4 keeps the start conductor 50 clear of the ground which would otherwise be applied to it at armature 11 of the line 55 relay, and it also maintains the winding of the cut-off relay 5 separate from the conductor 30 extending to the test banks of the finders. The line is marked busy in the banks of the connectors by ground applied to the test conductor 60 17 at armature 13 of the line relay 6.

65 Talking battery is fed to the line through the windings of the line relay 6, and the line equipment is therefore the only apparatus that is in use during conversation on a call of this character. The link circuit which was used to set up the connection has been restored to normal as described and is free for use in another connection. The subscriber at station A, in the call which has just been described, knows when the subscriber at station C answers the call because of the cessation of the ringing operation. The bell at station A being connected to the same side of the line as the bell at station C, both bells will ring in parallel and when his own bell stops ringing 75

the subscriber at station A knows that the subscriber at station C has answered. If a station had been called at which the bell is connected to the other side of the line the subscriber at station 8 A would not have heard the ringing, but he would have waited according to instructions for a long enough time to ring the desired station several times and then he would have removed his receiver.

10 The operation of certain features of the invention which are disclosed in Fig. 3 will now be considered. The first feature which will be explained is one which has to do with the operation of the relays 208 and 209. These relays are provided for the purpose of causing the finder distributor to step ahead and select another link circuit in case the finder of the link circuit in use is unable to find the calling line. This may happen from a variety of causes, for instance, the 15 test wiper 52 of the finder in the link circuit disclosed in the drawings may be bent or otherwise out of adjustment so that it does not properly close the test circuit. This will prevent the finder from stopping on the calling line. Obviously it 20 would be desirable to start another finder switch if such operation could be provided for.

When the start relay 207 pulls up responsive to the grounding of the start wire 50, in addition to the operations which this relay performs in the 25 regular course, all of which have been described hereinbefore, it prepares a circuit at armature 222 for relay 208. The reference character P indicates a pulse machine which is assumed to be continuously operating and which alternately 30 grounds conductors 244 and 243. These applications of ground may be at fifteen-second intervals. Assuming now that for some reason or other the finder in use fails to stop on the calling line and therefore no ground is received back on the conductor 250. The first time then that the 35 pulse machine places ground on conductor 243 relay 208 will operate and will close a locking circuit for itself at armature 225. Relay 208 closes at armature 224 a circuit for relay 209. Fifteen seconds later the pulse machine grounds conductor 244 and relay 209 operates, locking itself at armature 227. Relay 209 upon energizing 40 closes a circuit at armature 226 for the stepping magnet 213 of the finder distributor. The stepping magnet accordingly energizes and breaks the circuit of relay 207. Relay 207 falls back and 45 breaks the circuit of relay 208 and also the circuit of relay 209. Relays 208, 209, and 206 accordingly deenergize. The circuit of the stepping magnet 213 is therefore opened, the magnet deenergizes, and the wipers of the finder distributor are therefore advanced one step. As a result 50 the finder distributor is associated with the next link circuit. If the next link circuit is busy there will be a ground on the conductor such as 250, and as a result, therefore, relay 207 will be short circuited and a circuit will be completed by way of armature 228 and the interrupter contact of the stepping magnet 213 for automatically operating the magnet 213 again so as to advance the 55 wipers to the next link circuit. The finder distributor steps its wipers along in this way until wiper 201 reaches a conductor such as 250 which is not grounded, indicating that an idle link circuit has been found. The finder distributor then comes to rest and relay 207, being no longer short circuited, again energizes. The finder switch of the newly selected link circuit is then operated in the manner which has been heretofore described in order to hunt for and connect up the 60

calling line. It will be understood that the operation of the pulse machine provides a minimum interval of fifteen seconds within which the finder switch originally started locate and stop on the calling line, sending ground back on conductor 250. If this operation does not occur, the system is not held up pending the replacement of the receiver by the calling subscriber, as would ordinarily occur, but the finder distributor is automatically stepped ahead after the designated time 10 interval in order to select a new link circuit and start the finder thereof in operation.

The so-called "permanent lockout" feature of the system will next be explained. The term "permanent" is customarily applied to a sustained calling condition on a line, which may be due to a receiver being left off the hook at some station on the line, or it may be due to a ground or short circuit on the line. When such a condition occurs, the line concerned will, of course, 15 be picked up by the finder switch of an idle link circuit and the link circuit will await the receipt of dialling impulses. If no dialling impulses are received the link circuit would ordinarily be kept out of service indefinitely. The link circuits are 20 provided on a percentage basis and a few permanents therefore would tie up all of the equipment in the system and prevent other subscribers from setting up connections. In attended exchanges supervisory signals are employed to 25 notify the attendant of these conditions and the affected lines can be cut out of service so as to free the switch-board equipment. In an unattended exchange, however, it is necessary to provide arrangements for taking care of these 30 conditions without the assistance of an attendant. Such arrangements have been known before, but the one disclosed herein is believed to possess advantages over any that have been made heretofore.

For the purposes of explanation it will be assumed that the line associated with the line circuit #1, Fig. 1, becomes grounded. This will operate the line relay 6 in the usual manner, with the result that an idle link circuit is appropriated 45 for use through the medium of the finder distributor, Fig. 3. The finder of the link circuit will locate the line on which the calling condition is simulated, and will establish connection thereto preparatory to the receipt of dialling impulses. 50 So long as other link circuits remain in idle condition, so that if a genuine call is made in the system a link circuit will be found available, nothing further occurs as a result of the ground on the line in question. The line remains connected 55 through to the link circuit. It will be understood that the condition may be only temporary. Since a good many of these conditions clear themselves within a short time there is no use in locking out the line or doing anything special so long as idle 60 trunk circuits remain available for use. In the event that all the other link circuits become busy, however, it immediately becomes desirable to free the link circuit which is being held by the permanent.

When the link circuits all become busy, ground is removed from the common conductor 254. Relay 210, therefore, drops back. As explained before, relay 210 is normally energized and only falls back when all of the link circuits are taken 70 into use. Upon deenergizing, relay 210 opens the start circuit in the finder distributor at armature 231, and at armature 228 it opens the automatic hunting circuit for the stepping magnet 213. Relay 210 also closes at armature 230 a circuit for 75

relay 212. Upon energizing, relay 212 locks itself at armature 233, prepares a circuit for relay 211 at armature 238, and prepares a circuit for the stepping magnet 242 of the timer switch TS 5 at armature 236. Now when the pulse machine P grounds conductor 243 the next time a circuit will be completed by way of wiper 240 for the stepping magnet 242. The magnet therefore energizes momentarily, due to the fact that it 10 interrupts its own circuit, and advances the wipers of the switch one step. Wiper 240 is now standing on the second contact in its bank, which is connected to conductor 244, and no further operation takes place until the conductor 244 is 15 grounded in due course by the pulse machine P. The motor magnet 242 then advances the switch another step, bringing the wiper 240 into engagement with the third contact in its bank, which is connected to conductor 243. In this way the 20 timer switch TS is stepped ahead at intervals until eventually the wiper 241 arrives at the fourth contact in its bank, whereupon a circuit is completed for relay 211. Relay 211 locks itself at armature 233, breaks the circuit of the relay 212 25 at armature 234, and at armature 232 opens a point in the restoring circuit for the timer switch.

Finally, at armature 235, relay 211 disconnects ground from the supervisory ground conductor 257 extending to all of the link circuits. Assuming that the link circuit shown in Figs. 1 and 2 30 is the one which is being held by the "permanent", the removal of ground from the supervisory ground conductor will result in the de-energization of relays 65 and 66 and the link will 35 be released. Ground is removed from release trunk conductor 57 at the same time and the cut-off relay 5 in the line circuit #1 will fall back. Upon deenergizing relay 5 again connects up the line relay 6 and this relay accordingly 40 energizes due to the ground on the line. Upon energizing, relay 6 closes a circuit at its armature 11 for holding up relay 4 so that the latter relay remains operated notwithstanding that its original circuit is broken by the falling back of the 45 cut-off relay. The line is made busy by the application of ground at armature 13 of the line relay to the private normal conductor 17.

It will be seen from the foregoing that the link circuit which was seized by the grounded line 50 has been restored to common use and the line has been locked out by the holding up of relay 4. This relay keeps the start wire 50 open at armature 8, and at armature 7 keeps the cut-off relay disconnected from the conductor 30 so as to prevent 55 a calling condition being established in the banks of the finders. In the event that the ground on the line should clear itself, the line relay 6 will of course fall back and release relay 4. The line circuit is thereupon restored to normal 60 condition so that if a genuine call occurs on the line it can be handled in the usual way.

It will be noted also from the foregoing that 65 no attention is paid to permanents unless all of the link circuits become busy. Thus there may be three or four permanents at one time and nothing will be done unless the link circuits are all taken into use. When this occurs, the supervisory ground conductor is cleared of ground in the described manner and this releases all of 70 the link circuits which are falsely held up by lines which are not actually in use. In fact, all the link circuits are released except those which are actually engaged in conversation. In this connection it should be pointed out that when 75 conversation is taking place on any link circuit,

the relay such as relay 103, Fig. 2, will be energized, and ground from the supervisory ground conductor will be replaced by direct ground at such link circuit. This insures that the removal of ground from the supervisory ground conductor 5 for the purpose of locking out permanents will not release a link circuit on which conversation is actually taking place. The time interval which is counted off by the timer TS can be adjusted to suit the ideas of different operating companies 10 by changing the wiring at the banks of wiper 241.

The operations which take place in setting up a connection to a subscriber in a distant exchange will now be described. The tenth level of the connectors is reserved for one or more groups of 15 trunk lines extending to distant automatic exchanges. For example, there may be a group of four trunk lines extending from the exchange herein described to some distant automatic exchange with which service is to be given. If 20 there are other automatic exchanges the remaining six sets of contacts in the tenth level will provide facilities for one or more additional groups of trunks. There is nothing novel about the trunk circuits which are used for this purpose 25 and accordingly reference is made to Patent No. 1,528,751, granted March 10, 1925, to Bellamy et al., for a disclosure of a trunk circuit and associated repeater which is suitable for the purpose. Since the present system includes ground- 30 and accordingly reference is made to Patent No. 1,528,751, granted March 10, 1925, to Bellamy et al., for a disclosure of a trunk circuit and associated repeater which is suitable for the purpose. Since the present system includes ground- 35 and accordingly reference is made to Patent No. 1,528,751, granted March 10, 1925, to Bellamy et al., for a disclosure of a trunk circuit and associated repeater which is suitable for the purpose. Since the present system includes ground- 40 and accordingly reference is made to Patent No. 1,528,751, granted March 10, 1925, to Bellamy et al., for a disclosure of a trunk circuit and associated repeater which is suitable for the purpose. Since the present system includes ground- 45 and accordingly reference is made to Patent No. 1,528,751, granted March 10, 1925, to Bellamy et al., for a disclosure of a trunk circuit and associated repeater which is suitable for the purpose. Since the present system includes ground- 50 and accordingly reference is made to Patent No. 1,528,751, granted March 10, 1925, to Bellamy et al., for a disclosure of a trunk circuit and associated repeater which is suitable for the purpose. Since the present system includes ground- 55 and accordingly reference is made to Patent No. 1,528,751, granted March 10, 1925, to Bellamy et al., for a disclosure of a trunk circuit and associated repeater which is suitable for the purpose. Since the present system includes ground- 60 and accordingly reference is made to Patent No. 1,528,751, granted March 10, 1925, to Bellamy et al., for a disclosure of a trunk circuit and associated repeater which is suitable for the purpose. Since the present system includes ground- 65 and accordingly reference is made to Patent No. 1,528,751, granted March 10, 1925, to Bellamy et al., for a disclosure of a trunk circuit and associated repeater which is suitable for the purpose. Since the present system includes ground- 70 and accordingly reference is made to Patent No. 1,528,751, granted March 10, 1925, to Bellamy et al., for a disclosure of a trunk circuit and associated repeater which is suitable for the purpose. Since the present system includes ground- 75 and accordingly reference is made to Patent No. 1,528,751, granted March 10, 1925, to Bellamy et al., for a disclosure of a trunk circuit and associated repeater which is suitable for the purpose.

It will be assumed that there is a group of four trunks terminated in the first four contact sets of the tenth level, each trunk extending 40 by way of a repeater to the distant automatic exchange, where it terminates in the usual incoming first selector switch. Each trunk line comprises three conductors, the two line conductors and a test conductor. The two line conductors are, of course, connected in the upper and lower banks of the connectors. The test conductor or release trunk conductor is connected in the upper test bank of the connectors. That is, the bank which is associated with the wipers 50 such as wiper 183 of the connector shown. Only the first trunk line of the group is indicated in the drawings. This trunk line comprises conductors 501, 502, and 503. Conductors 501 and 503 are the line conductors, while conductor 502 55 is the test or release trunk conductor.

Since a group of trunk lines is provided for handling calls to the automatic exchange in question, the connectors such as the one shown in the drawings must be arranged to operate as 60 rotary connectors. This is an operation which is well understood, and merely means that the subscriber in calling the distant exchange will dial the number of the first trunk line in the group. If this trunk line is idle it will be seized 65 and the connection will be extended thereover. If the first trunk line is busy, however, the connector will automatically rotate in search of an idle trunk line. The circuits for controlling the automatic rotary operation of the connector disclosed in this case are very similar to the circuits which are illustrated in the patent to Wicks, No. 1,644,968, granted October 11, 1927. It will not be necessary, therefore, to explain the arrangement in great detail. It may be stated that 75

- the wiper 184 of the connector is an additional wiper which is provided for use in controlling the automatic rotary movement of the switch and has no other function. All test contacts which are accessible to wiper 184 are strapped to the corresponding test contacts which are accessible to wiper 183, except in the case of the last test contact of each group. This means that as regards the group of trunk lines under discussion, the first, second, and third test contacts of the naught level which are accessible to wiper 184 will be strapped to the first, second and third test contacts in the naught level which are accessible to test wiper 183. The fourth test contact accessible to wiper 184, which belongs to the last trunk line of the group, is not strapped, and this provides for stopping the connector on this last trunk line in the event that it is busy.
- It will be assumed now that the subscriber at station A on the line which is associated with line circuit #1, Fig. 1, desires to extend a connection to the distant automatic exchange. In order to accomplish this the subscriber must dial a preliminary number 01, followed by the regular number of the desired subscriber in the distant exchange. When the receiver is removed at station A, the heretofore described operations take place by means of which the line is picked up by an idle link circuit. It will be assumed that the link circuit shown in Figs. 1 and 2 is taken into use. When the subscriber dials the first digit 0 of the number, ten impulses are transmitted to the vertical magnet 180 and the shaft of the switch is stepped up until the wipers are opposite the tenth level. When the shaft reaches the tenth level, the level off normal springs LN¹ and LN² are closed. Springs LN² connect up the test wiper 183, while springs LN¹ prepare a circuit for the switching-through relay 104.
- The subscriber may now dial the digit 1. As a result the rotary magnet 181 receives one impulse of current whereby the connector shaft is rotated one step and the wipers 182 to 185, inclusive, are brought into engagement with the first set of contacts in the tenth level. Relay 108 is energized in parallel with the rotary magnet 181, as described hereinbefore and closes a circuit for relay 109. Only the functions of these relays which have to do with the automatic rotary movement will be described at this time. Upon energizing relay 109 closes a circuit from the grounded release trunk conductor 57 by way of armature 152, the level off normal springs LN¹ and the lower winding of the switching-through relay 104 to battery. The lower winding of relay 104 is an inefficient winding and consequently the relay is only partly operated, just sufficient to close the contacts labeled X in the drawings. The closure of the contacts X by armature 125 completes a circuit which extends from the grounded release trunk conductor 57 by way of back contact of armature 132 of the busy relay 105, contacts X, upper winding of switching-through relay 104, and the lower winding of said relay to battery. The upper winding of relay 104 is, however, at this time short circuited due to the operation of relay 109 and consequently nothing further happens.
- At the end of the directive rotary movement of the switch, relay 108 falls back, and closes a circuit for the busy relay 105. If the first trunk line is busy the busy relay 105 will operate from ground on the contact engaged by wiper 183, and at armature 131 connects up the auxiliary test wiper 184. Since the two first test contacts are strapped together, wiper 184 will also find ground and a circuit will be completed by way of the said test wiper 184, armature 151, armature 131, contacts controlled by armature 157, armature 162, interrupter contact of the rotary magnet 181, and the winding of relay 110 to battery. Relay 110 accordingly energizes, at armature 157 completes a locking circuit for itself, and at armature 199 completes a circuit for the rotary magnet which extends from ground at armature 108, by way of armature 160, armature 199, and the winding of the rotary magnet 181 to battery. Upon energizing, the rotary magnet 181 advances the switch wipers on to the next set of contacts, and at the same time breaks the circuit of relay 110. The relay accordingly falls back and breaks the rotary magnet circuit. If the next set of contacts is busy the same operation will be repeated, and the rotation of the switch will continue until an idle trunk line is reached. It will be observed that relay 109 is connected in parallel with the rotary magnet 181 by way of armature 145, armature 149, armature 144, and armature 164, so that while impulses are being transmitted to the rotary magnet as described in the foregoing, these impulses also are received by relay 109 and serve to maintain it energized.
- If all of the trunks are busy the rotation will continue until the last trunk line of the group is seized at which time the auxiliary test wiper will find no ground potential due to the fact that the two test contacts associated with this trunk are not strapped together. Accordingly rotation of the switch will cease and the busy relay 105 will lock itself energized following the deenergization of relay 109, transmitting a busy signal to the calling subscriber in the manner heretofore described.
- It will be assumed now that some trunk line is found to be idle, and for convenience this will be taken as the first trunk line of the group, the one indicated in the drawings. When the relay 108 falls back then at the end of the directive rotary movement of the switch the test wiper 183 will not find ground and no circuit will be completed for the busy relay 105. Relay 105, accordingly remains deenergized. An instant later relay 109 falls back and at armature 152 removes the shunt from the upper winding of the switching-through relay 104. Relay 104 therefore completely energizes. As a result, test wiper 183 is connected to the release trunk conductor 57 at armature 198. This immediately places ground on the test contact of the selected trunk to make it busy. In addition, the talking circuit conductors 55 and 56 are connected through directly to wipers 182 and 185 of the connector, exclusive of the repeating coil windings and all connections to battery and ground. Relay 104 also opens the release circuit at armature 128, and at armature 127 it opens the supervisory ground circuit so as to prevent closing the impulsing circuit when the lock-pulse relay 64 falls back.
- The calling line has now been extended by way of wipers 182 and 185 and trunk conductors 501 and 503 to the repeater. The line relay of the repeater accordingly energizes and closes a circuit for the release relay. Upon energizing the release relay grounds conductor 502 and this provides holding ground for maintaining the relay 104 of the connector in operated position. The test wiper 183 has already been joined to the release trunk conductor 57, as described, and ground is therefore supplied for holding up the relays 60 and 5 also. It is understood that this

ground is fed back from the repeater before the release relay 65 of the connector has had time to fall back.

It will not be necessary to describe in detail the operation of the automatic switches in the distant automatic exchange. Suffice it to say that when the digits of the subscriber's number are called, corresponding series of impulses are repeated by the repeater in the trunk line and serve to operate the necessary automatic switches in the usual manner to complete the connection. When the subscribers are through talking they will hang up their receivers and the replacement of the receiver at the station A will bring about the deenergization of the line relay of the repeater. On falling back, the line relay breaks the circuit of the release relay and this relay therefore deenergizes to unground the release trunk conductor 502. The apparatus is therefore restored to normal in a manner which will be readily understood.

The trunk circuit shown in Fig. 5 will now be described. The community exchange, to which this invention relates, may be trunk connected with a manual exchange as well as with an automatic exchange, and the trunk circuits for connecting with the manual exchange may be of the type shown in Fig. 5. It will be assumed that there is a group of these trunks which extend from jacks such as J at the manual exchange in question and line equipments in the C. A. X. similar to the line circuit #1, Fig. 1. The normal conductors associated with the line circuits may be multiplied in any level of the connector banks except the tenth level, which is reserved for switching through to automatic trunks as has been described hereinbefore. Preferably, however, these manual trunks should not be terminated in the sixth level as this level is set aside for the use of large party lines. Any other level, as for example, the fifth level, will serve the purpose. In the case of the trunk circuit shown in Fig. 5, therefore, it will be understood that jack J is located at the switchboard in the distant manual exchange. The conductors 432, 437 and 433 extend to a line equipment which is the same as the line circuit #1, Fig. 1. The normal conductors 436, 437, 438, and 439 extend to the connector banks and may be connected to the first set of contacts in the fifth level, where they are accessible to wipers 182 to 185, respectively.

For the purposes of the explanation, it will be assumed first that the operator at the manual exchange desires to complete a connection to some subscriber in the C. A. X. The operator will therefore insert the calling plug of an idle cord circuit in the jack J. The cord circuit may be of the well known common battery type which is in common use. Upon inserting the plug in the jack a circuit is completed in an obvious manner for the relay 401, which energizes by current supplied from the cord circuit. Relay 401 is of high resistance and does not operate the supervisory relay in the cord circuit. Upon energizing, relay 401 connects up the sleeve relay 403 at armature 410. Relay 403 operates and locks itself to the sleeve of the jack at armature 413. Relay 413 also prepares locking circuits for relays 405 and 406 at armature 414, and at armature 416 it disconnects the ring-down relay 404 from in bridge of the trunk. At the front contact of armature 416 the lower trunk conductor 433 is extended to the lower right hand winding of the repeating coil, with the result that a

loop is completed which includes the polarized relay 402.

Upon the completion of the loop circuit in the manner described above, the line relay of the associated line equipment at the C. A. X. operates in the usual manner and through the medium of the finder distributor an idle link circuit is taken into use. Assuming that the link circuit shown in Figs. 1 and 2 is the one selected, the finder will operate in the usual manner to connect the link circuit with the trunk line over which the call has been received. The line relay 100 of the link circuit is therefore energized over the loop in series with the polarized relay 402 at the operator's position. The direction of current flow at this time is such that the polarized relay 402 is not operated.

The operator will now throw the dial key K so as to connect her calling device across the trunk line conductors 432 and 433, the calling device being substituted for the bridge including the repeating coil and polarized relay 402. The operator will now operate the calling device in accordance with the digits of the required number. When the calling device is operated the first time a circuit is completed for relay 406, which energizes and locks itself at armature 420. The operation of the calling device is effective to control the connector and the code selecting switch CS in the manner heretofore described so as to connect with and signal the desired called subscriber. On completion of the dialling operation, the operator restores the key K, so that the polarized relay is again included in the loop circuit which extends over the trunk to the C. A. X.

When the called subscriber answers relays 63, 103 and 107 operate as hereinbefore described, and the latter relay stops the signalling operation. Relay 103 reverses the direction of current flow over the trunk, operating the polarized relay 402. Upon energizing relay 402 connects the upper winding of relay 405 in shunt with relay 401 at armature 411, and since the upper winding of relay 405 is of relatively low resistance the supervisory relay in the cord circuit now operates, extinguishing the supervisory lamp. This informs the operator that the called party has answered.

Conversation between the party at the manual exchange and the local C. A. X. subscriber may now take place in the usual manner. When the subscribers are through talking they hang up their receivers and the supervisory lamps are accordingly lighted at the operator's cord circuit. The calling supervisory lamp is lighted by the falling back of the polarized relay 420, which is brought about by the reversal of the current back to normal by the falling back of the relay 103 of the connector. This latter relay, of course, restores under control of relay 63 when the called man hangs up his receiver. On observing the lighted supervisory lamps, the operator will pull down the connection and the equipment at the C. A. X. is restored to normal in the usual manner.

A call which is extended from a calling subscriber in the C. A. X. to a subscriber in the manual exchange will now be considered. It will be assumed for this purpose that the calling subscriber is the subscriber at station A. The number which is to be called is number 511, which corresponds with the previously described connection of the trunk lines in the connector banks. The final digit 1 of the number, it may be mentioned, is determined by the fact that it is desired

to use individual line ringing for signalling over the trunk line rather than some code ring.

When the receiver is removed at station A a link circuit is taken for use in the manner previously described. It will be assumed that the link circuit shown in Figs. 1 and 2 is the one which is taken for use. Upon dialling the digit 5 followed by the digit 1, the connector is set on the first set of contacts in the fifth level, this being the set of contacts in which the trunk line shown in Fig. 5 is terminated. The connector wipers 182 to 185, inclusive, are therefore in engagement, respectively, with bank contacts to which normal conductors 436 to 439 are connected.

Upon dialling the last digit of the number, the digit 1, the code selector CS is operated one step, and the ringing circuit is connected up to the individual line ringing conductor 339, Fig. 4. The trunk line is now tested in the usual way and assuming that it is found to be idle, the connector seizes it in the usual manner and the ringing operation is started. These operations have already been described in detail and hence need only brief mention at this time.

When the ringing current is transmitted over the trunk line, ring-down relay 404, Fig. 5, is operated, and locks itself at armature 417. Relay 404 closes a circuit for the call signal lamp associated with the jack J, thus notifying the operator that a call has been received over the trunk line. The operator therefore plugs into the trunk with an idle cord circuit in order to answer the call. When the plug is inserted in the jack J relay 401 operates and connects up the sleeve relay 403. Relay 403 operates and locks itself to the sleeve at armature 413. At the back contact of armature 414 relay 403 unlocks the ring-up relay 404, which accordingly deenergizes and puts out the call lamp. At the front contact of armature 414 relay 403 prepares a locking circuit for relay 405. At armature 415 relay 403 prepares a circuit which will shortly be described, and at armature 416 it bridges the right hand winding of the repeating coil and the polarized relay 402 across the conductors of the trunk. The loop circuit is thus closed and relays 62 and 63 of the connector are accordingly energized, these two relays feeding current to the trunk circuit in the usual manner. Relays 103 and 107 are also energized, the latter relay stopping the ringing operation. It will be observed that the normal conductors 436 and 439 are reversed between the line circuit equipment and the connector banks so that the current flow over the trunk line is now in the proper direction to operate the polarized relay 402. This relay accordingly energizes and at armature 411 connects the upper winding of relay 405 in shunt with relay 401. This operation controls the supervisory lamp in the cord circuit in the manner previously described. The operator will now speak to the calling party and ascertain his wants, after which the desired connection is completed manually by inserting the other end of the cord circuit in the jack of the desired line.

It will be assumed now that the wrong number has been obtained or that for some other reason the subscriber at station A desires to recall the operator. In order to do this the subscriber "flashes" his switch-hook, which means that he depresses it momentarily a number of times. When the receiver hook is depressed, the calling line circuit is broken and the relay 100 falls back, followed by lock-pulse relay 64. Relay 64, upon deenergizing, breaks the connection of relay 63

to the upper wiper 182 of the connector. This opens up the battery feed circuit over which current has been supplied to the trunk through relays 63 and 62 in series, holding up the polarized relay 402 at the manual exchange. When the circuit is broken in this manner, relay 402 falls back and by opening its contact 411 the shunt is removed from relay 401 and the lamp in the operator's cord circuit is lighted. At the same time relay 402 closes a circuit which extends from battery by way of a resistance to the back contact of armature 421, armature 419, armature 415, and armature 412, to the upper trunk conductor 432. From this point the circuit extends by way of normal conductor 439 and the lower connector wiper 185 to relay 62, which is thus held in energized position. Relay 62 may be slightly slow-acting so as not to fall back when its initial circuit is broken. However, it will do no harm if this relay falls back momentarily. When relay 63 falls back, a circuit is completed which extends from the supervisory ground conductor by way of armature 73 of relay 63, armature 71 of relay 62, and the winding of release relay 65 to battery. Release relay 65 is accordingly held energized so as to hold up the link circuit and prevent the connection being released, notwithstanding that the hook-switch is depressed at the calling station.

When the hook-switch rises at the calling station relays 100 and 64 pull up again, a circuit having been prepared for the latter relay at armature 72 of relay 62, and the latter relay again connects up relay 63, thus reclosing the circuit for supplying current to the trunk circuit over the connector wipers. Relay 402 is accordingly energized again and at armature 411 relay 401 is shunted down again to put out the lamp at the operator's cord circuit. Relay 402 also removes battery from the upper trunk conductor 432. Relay 62 now holds up in series with relays 63 and 402 as before. These operations may be repeated several times as the subscriber flashes his switch-hook in the well known manner, resulting in the interrupted operation of the supervisory lamp in the operator's cord circuit to notify her that her attention is required.

In view of the arrangements for recalling the operator which have just been described, it will be understood that the release of the connection is under the control of the operator. When the calling subscriber at station A replaces his receiver, the described operations result in the lighting of the supervisory lamp at the operator's cord circuit, and since the lamp remains lighted steadily the operator will understand that the parties are through with the connection. She will, therefore, remove the plugs from the jacks. When the plug is removed from the jack J the sleeve relay 403 is deenergized and at armature 415 the circuit by which holding battery is connected to the upper trunk conductor 432 is broken. This permits relay 62 of the connector to fall back and open the circuit of the release relay 65. The other circuits of this relay have already been opened by the falling back of the line relay 100 and the lock-pulse relay 64, so that the release relay 65 now deenergizes. The other relays in the connection are deenergized in the usual way and the connector is restored to normal as previously described.

The invention having been described, what is considered to be new will be pointed out in the appended claims.

What is claimed is:

1. In an automatic switch, a line relay, a pulse

- relay, an initial energizing circuit for said pulse relay closed by the line relay on energizing, a locking circuit for said pulse relay opened by said line relay on deenergizing, means for opening said initial energizing circuit prior to the opening of said locking circuit so that when the line relay again energizes the said initial energizing circuit will not be closed, a stepping circuit closed by said pulse relay on deenergizing, and means controlled over said stepping circuit for deenergizing said pulse relay and causing the same to close said locking circuit.
2. In an impulse repeating arrangement, a line relay and a line over which it is energized, a pulse relay, an initial energizing circuit for said pulse relay closed by said line relay, a locking circuit for said pulse relay, means for opening the said initial energizing circuit, said locking circuit being under control of said line relay whereby when the line relay deenergizes responsive to the first interruption of a series the pulse relay will de-energize, a circuit in which impulses are produced by deenergizations of said pulse relay, and means controlled over said circuit responsive to each impulse for reoperating said pulse relay.
3. In combination, a circuit, a relay for closing said circuit on deenergizing in order to produce an impulse therein, means controlled over said circuit for reoperating said relay to terminate the impulse each time one is produced, and means including a line relay responsive to a series of digital impulses for controlling the deenergizations of said first relay.
4. In an automatic switch, a line relay, a stepping magnet, a pulse relay controlled at a front contact of said line relay, and a circuit for said stepping magnet controlled at a back contact of said pulse relay.
5. In an automatic switch, a line relay energized when the switch is seized, a pulse relay initially energized responsive to the energization of said line relay and deenergized responsive to the deenergization of said line relay, means for preventing said pulse relay from energizing when the line relay energizes the second time, a stepping magnet, a circuit for said magnet closed by said pulse relay upon deenergizing, and a circuit for energizing said pulse relay controlled by said magnet.
6. In an automatic telephone system, a group of automatic switches accessible to calling lines, means whereby said switches are seized and made busy responsive to calling conditions on said lines, timing means, means for starting said timing means responsive to all said switches being in seized condition at the same time, and means controlled by said timing means for restoring all said switches to common use.
7. A system as set forth in claim 6, characterized by the provision of means which in the event that one of said switches is included in a conversational circuit at the time the restoration takes place will prevent the restoration of such switch.
8. In an automatic telephone system, a plurality of automatic switches for extending calling lines, means for seizing one of said switches responsive to a calling condition on one of said lines, means for freeing the seized switch if dialling impulses are not received within a predetermined time, means for operating said last means only when all of said switches are in use, and means for preventing the continuance of the calling condition on said line from causing the reseizure of the same switch or the seizure of another switch.
9. In an automatic telephone system, a switch for use in connecting calling and called lines, a relay which is energized responsive to the answering of a called subscriber, a conductor supplying holding ground to said switch, means external to the switch for removing ground from said conductor, and means controlled by said relay for supplying a local ground to the switch independent of said conductor so that if ground is removed therefrom during conversation the switch will not be released.
10. In an automatic telephone system, party lines, means including connector switches controllable over calling lines to connect with called lines, means whereby the subscriber on one of said party lines can seize one of said connectors and operate the same to connect with his own line, means for giving the calling party a busy signal, means responsive to the replacement of the receiver at the calling station for grounding the test wiper of the connector in use, thereby extending holding ground to the release trunk of said connector by way of the private normal conductor of the calling line, means for opening the incoming talking conductors to said connector while the same is maintained by said holding ground, means for signalling the called subscriber through a talking wiper of said connector, means for releasing the connector when the calling or the called subscriber removes the receiver, and means individual to the calling line for supplying talking current.
11. In a telephone system, a trunk line incoming to a connector switch, said trunk line including a release trunk conductor, a line relay in said switch, a slow-acting release relay controlled by said line relay for grounding said release trunk, a second slow-acting relay in said switch energized by ground on said release trunk, a release magnet in said switch controlled by said second relay, and means controlled by the replacement of the receiver on the calling line when the switch is being used for a reverte call for grounding said release trunk, whereby the said second relay is held up to maintain the switch operated after the line relay and the release relay have deenergized.
12. In an automatic telephone system, a connector switch, switching mechanism for extending a calling line to said connector, a release trunk conductor extending between said mechanism and the connector to hold the connection, a private normal conductor individual to the calling line over which busy potential is extended to the test bank of said connector, said normal conductor being temporarily connected to said release trunk conductor, means for operating said connector to select a called line, and means responsive to the replacement of the receiver at the calling line for grounding the test wiper of said connector if the called line was found busy, whereby if the called line is also the calling line a ground potential will be extended by way of the private normal conductor to said release trunk conductor to prevent the release of the connection.
13. In an automatic telephone system, party lines, a connector switch controlled from any one of said lines to select the same or another line, a seizing relay in said switch operated if the called line is idle, a busy relay operated if the called line is busy, said busy relay preventing the normal operation of said seizing relay, and means respon-

- sive to the replacement of the receiver while the busy relay is operated for operating said seizing relay, said last means being effective only if the same line has been selected.
- 6 14. In an automatic switch, a line relay, said relay having a stiff adjustment so that it will respond to rapid interruptions of a leaky line, a priming circuit for the line relay, and back contacts on the line relay for closing said priming 10 circuit to enable the line relay to respond to rapid interruptions of a high resistance line.
15. In combination, a line, a line relay controlled by interruptions in said line to transmit impulses, a stiffly adjusted spring for causing 15 said relay to retract its armature quickly, a local priming circuit for causing the line relay to quickly attract its armature, and means for opening said priming circuit when the armature is attracted.
- 20 16. In an automatic switch, a line relay, a lock-pulse relay controlled by said line relay, a stepping magnet controlled by said lock-pulse relay, a release relay for supplying holding potential to the release trunk conductor incoming to said 25 switch, and a circuit for said release relay controlled jointly by said line relay and said lock-pulse relay.
- 25 17. In an automatic switch as set forth in claim 16, a second release relay, a circuit for said second release relay including a portion of said release trunk conductor, and a release magnet for said switch controlled by said second release relay.
- 30 18. In an automatic connector switch, means responsive to two successive series of impulses for operating said switch to set its wipers on a called line, means responsive to a further series of impulses for causing said connector to test the idle or busy condition of the called line, and 35 means effective if the first series of impulses is of a particular value for causing said connector to test the idle or busy condition of the called line responsive to the second series of impulses.
- 35 19. In a telephone system, two kinds of subscribers' lines, means including an automatic switch for extending a connection from any calling line, means in said switch for reversing the direction of current flow over the calling line, and means effective only if a particular kind of line 40 is calling for rendering said reversing means ineffective.
- 40 20. In an automatic telephone system, a code ringing connector, a code selector associated with said connector and having two wipers, code ringing conductors selectable by one wiper, other code ringing conductors selectable by the other wiper, a wiper selecting relay, means for operating said relay to substitute one of said wipers for the other when the connector is operated to select one group 45 of contacts in its bank but not if the connector is operated to select another group of contacts, and a party line which has an appearance in both groups of contacts.
- 45 21. In an automatic connector switch, a line relay, a release relay controlled by said line relay, two separate battery feed relays connected in bridge of the talking wipers of said switch in series with a battery, and a circuit for said release relay controlled jointly by said battery feed relays.
- 50 22. In an automatic telephone system, grounded lines, metallic circuit lines, local battery lines, common battery lines, party lines, trunk lines extending to a distant exchange, automatic connector switches accessible in common to all of 55 said lines, and means for controlling one of said
- connectors over any calling line to complete a talking connection to any other line in the system.
- 5 23. In an automatic telephone system, party lines, means including link circuits controllable over calling lines to connect with called lines, means whereby the subscriber on one of said lines can seize one of said link circuits and operate the same to connect with his own line, means for giving the calling party a busy signal, means responsive to the replacement of the receiver by 10 the calling party for grounding the outgoing test conductor of link circuit in use, thereby extending holding ground to the release trunk of said link circuit by way of the test conductor of the calling line, means for opening the incoming talking conductors to said link circuit while the same is maintained by said holding ground, means for signalling the called subscriber over a talking conductor of said link circuit, means for releasing the link circuit when the calling or called party removes the receiver, and means individual to the calling line for supplying talking current.
- 15 24. In an automatic telephone system, party lines, means including link circuits controllable over calling lines to connect with called lines, 20 means whereby the subscriber on one of said lines can seize one of said link circuits and operate the same to connect with his own line, means for giving the calling party a busy signal, means responsive to the replacement of the receiver by 25 the calling party for grounding the outgoing test conductor of the link circuit in use, thereby extending holding ground to the release trunk of said link circuit by way of the test conductor of the calling line, means for opening the incoming 30 talking conductors to said link circuit while the same is maintained by said holding ground, means for signalling the called subscriber over a talking conductor of said link circuit, means for removing said holding ground from the test conductors of the calling line and link circuit and from said release trunk conductor to release said link circuit when the calling or called party removes the receiver, means individual to said calling line operated in response to the removal of 35 holding ground from the test conductor of the calling line, a line relay individual to said line operated over said line in response to the operation of said individual means for supplying talking current to said calling line, and lock-out 40 means individual to said line originally operated by said individual means and maintained operated by said line relay for preventing the seizure of a link during the time said line is in use in a reverting call.
- 45 25. In an automatic telephone system, party lines, means including link circuits controllable over calling lines to connect with called lines, means whereby the subscriber on one of said lines can seize one of said link circuits and operate 50 the same to connect with his own line, means for giving the calling party a busy signal, means responsive to the replacement of the receiver by the calling party for grounding the outgoing test conductor of the link circuit in use, thereby extending holding ground to the release trunk of said link circuit by way of the test conductor of the calling line, means for opening the incoming talking conductors to said link circuit while the same is maintained by said holding ground, means for signalling the called subscriber over a talking conductor of said link circuit, means individual to said calling line operated over the test conductor thereof in response to the removal of holding ground therefrom for connecting talking cur- 55
- 60 70 75

rent thereto, and lockout means for preventing the seizure of a link circuit during the time said line is in use in a reverting call.

26. In a telephone system, a party line, a holding conductor individual thereto, switching apparatus, means for operating said switching apparatus to connect with said line, a cut-off relay individual to said line operated over said holding conductor in response to said connection, a line lock-out relay individual to said line operated in response to the operation of said cut-off relay, means for connecting a potential to said holding conductor to maintain said switching apparatus and said cut-off relay operated after the replacement of the receiver by the calling party in case the calling party is on the same line as the called party, means for releasing said switching apparatus and said cut-off relay in response to the removal of the receiver by the calling or called party, and a line relay individual to said line thereafter operated in response to the release of said cut-off relay for maintaining said lock-out relay operated.

27. In a telephone system, a party line, two talking conductors and a holding conductor individual to said line, switching apparatus including two incoming talking conductors and two outgoing talking conductors, means responsive to a call on said line for connecting the talking conductors of said line to the incoming talking conductors of said apparatus, means for operating said apparatus over said connected talking conductors to connect said outgoing talking conductors to said line conductors, means for connecting a potential to said holding conductor to maintain said outgoing conductors in connection with said line conductors and to disconnect said incoming talking conductors from said line conductors in response to the replacement of the receiver by the calling party, means for releasing said switching apparatus to disconnect said outgoing talking conductors from said line conductors and to disconnect said potential from said holding conductor in response to the removal of the receiver by the calling or called party, means individual to said line initially operated in response to said first connection and thereafter maintained operated as long as said potential is connected to said holding conductor, line lock-

out means individual to said line operated by said operated individual means, and other means individual to said line for maintaining said lockout means operated after disconnection of said potential from said holding conductor when said first individual means releases. 5

28. In a telephone system, switching means, a called line, a calling line and means for extending it to said switching means, a relay in said switching means connected from one conductor 10 of said line to ground, a second relay in said switching means connected from the other conductor of said line to the non-grounded pole of the exchange battery, a shunt circuit normally connected to ground for shunting said first relay 15 thereby shunting the impedance of the first relay from the line circuit, means for dialling over the line circuit to cause deenergizations of said second relay, means controlled by said second relay for operating said switching means to connect 20 with the called line, and means for opening said shunt circuit after completion of the dialling periods and the connection with the called line to include the impedance of said first relay in the line circuit. 25

29. In a telephone system, a called line, switching means, a line circuit in said switching means including a pair of line relays, means in said switching means for normally shunting out the impedance of one of said line relays, means controlled over said line circuit in response to dialling the digits in the telephone number of the called line for operating the other line relay and said switching means to complete a connection 30 with the called line, and means operated after the called number has been dialled for opening said shunting means to include the impedance of said one relay in the line circuit. 35

30. In an automatic telephone system, grounded lines, metallic circuit lines, local battery lines, common battery lines, party lines, trunk lines extending to a distant exchange, finder-connector links having access in common to all of said lines, a finder distributor for allotting idle ones of said links for use in a call over any of said lines, and means for controlling the allotted one of said links over any calling line to complete a talking connection to any line in the system. 40 45

NORMAN H. SAUNDERS.
